WILLIAM P. PITTS, OF INDEPENDENCE, MISSOURI, ASSIGNOR TO IRVING-PITT MANUFACTURING COMPANY, OF KANSAS CITY, MISSOURI, A CORPORATION OF MISSOURI.

LOOSE-LEAF BINDER.

1,092,287.

Specification of Letters Patent.

Patented Apr. 7, 1914.

Application filed May 12, 1913. Serial No. 766,997.

To all whom it may concern:

Be it known that I, WILLIAM P. PITTS, a citizen of the United States, residing at Independence, in the county of Jackson and State of Missouri, have invented a certain new and useful Improvement in Loose-Leaf Binders, of which the following is a specification.

My invention relates to improvements in loose leaf binders.

One of the objects of my invention is to provide a simple, cheap, durable and effective mechanism for clamping the follower of a loose leaf binder to the posts thereof.

The novel features of my invention are hereinafter fully described and claimed.

In the accompanying drawings which illustrate the preferred embodiment of my invention Figure 1 is a horizontal, longitudinal, sectional view, a portion of the upper cover being broken away. Fig. 2 is a view showing the base and posts in side elevation, the follower and parts connected therewith being shown in vertical section, the section being taken on the line *a*—*b* of Fig. 1. Fig. 3 is a cross section on the line *c*—*d* of Fig. 1, the view being enlarged. Fig. 4 is a cross section on the line *e*—*f* of Fig. 5. Fig. 5 is a fragmental, sectional view, enlarged, on the line *g*—*h* of Fig. 3.

Similar characters of reference designate similar parts in the different views.

1 designates the base member, to which are secured upwardly extending parallel posts 2.

3 is a tubular follower, provided with end caps 4 and 5, and having two holes 6, adapted to receive the posts 2. Longitudinally slidable in the follower 3, is a clamping member comprising preferably a horizontal flat plate 7, having at one end a downwardly turned portion 8, for supporting that end of the plate in a medial position in the follower 3. The other end of the clamping member 7 is provided with a slot 9, which is adapted to receive therethrough the adjacent post 2. The member 7 is provided with a hole 10, for receiving therethrough the other post 2. The outer end of the slot 9 is contracted, that portion of the member 7 being provided with inwardly extending portions 11, which are fitted in a transverse slot 12, Fig. 5, provided in the outer side of a nut 13, which is fitted in the wider portion of the slot 9, and has rotatably fitted in

it a horizontal adjusting screw 14, which at its outer end is squared to receive in operative engagement therewith the shank of a key or wrench, not shown, which is adapted to be inserted through a hole 15, which is 60 provided in the cap 4.

The inner end of the screw 14, is provided with a head 16, which at one end rotatably bears against a clamping member 17, which is adapted to clampingly engage the adjacent post 2. The other end of the head 16 is embraced by a vertical stop comprising an inverted U-shaped plate 18, the upper end of which is mounted in a slot 19, provided in the upper side of the follower 3. 70 The arms of the inverted U-shaped stop 18 embrace opposite sides of the screw 14, and are in turn embraced on their outer sides by two backwardly and inwardly turned arms 20, with which the clamping member 17 is 75 provided.

The clamping member 17 is fitted in the slot 9 of the member 7, so as to be incapable of rotation therein. The arms of the stop 18 preferably extend to a point below the 80 arms 20 of the clamping member 17 and are provided at their outer edges, as shown in Fig. 3, with laterally extending projections or shoulders 21, which bear against the lower edges of the arms 20, thereby holding 85 the stop 18 from becoming detached from the clamping member 17. The slot 19, in the top of the follower 3, is wide enough to permit a small movement of the stop 18, lengthwise of the follower 3. 90

In assembling the mechanism, the cap 4 is removed and the clamping plate 7 having mounted thereon the nut 13, screw 14, and clamping member 17, is inserted into the follower 3. The stop 18, is then passed 95 through the slot 19, with the arms of said stop inserted between the head 16 and the arms 20. The stop 18 is then driven home to the position shown in Fig. 3, with the projections 21 below the arms 20, said arms 100 being sufficiently resilient to permit them to spread apart while the projections 21 are being forced downwardly therebetween. After the stop 18 has been forced to its proper position, the arms 20 will resume 105 their original position and the stop 18 will be securely held. The posts 2 are then inserted through the holes 6 of the follower and through the slot 9 and hole 10 respectively, of the clamping member 7. The fol- 110

lower may now be moved to any desired position and held in such position by applying the wrench or key to the squared outer end of the screw 14 and turning said screw in a direction such that the member 7 will be forced to the clamping position, in which position the clamping member 17 will bear tightly against the adjacent post 2, and that portion of the clamping member 7 which forms the outer edge of the hole 10 will bear tightly against the other post 2. By having the member 17 non-rotatable, the post against which it bears will not be mutilated when the screw 14 is turned so as to effect a clamping engagement.

I do not limit my invention to the structure shown and described, as modifications thereof, within the scope of the appended claims, may be made without departing 20 from the spirit of my invention.

Having thus described my invention, what I claim and desire to secure by Letters Patent is:—

1. In a loose leaf binder, a tubular follower having a hole therethrough adapted to receive a post, a clamping member longitudinally movable in said follower and provided with a slot for receiving said post, a nut carried by said clamping member, an adjusting screw fitted in said nut, a second clamping member movable longitudinally in said slot by said adjusting screw, and a stop engaging said second clamping member and said tubular follower for limiting the movement of said second clamping member.

2. In a loose leaf binder, a tubular follower having a hole therethrough for receiving a post, a clamping member longitudinally movable in said follower and provided with a slot for receiving said post, a nut carried by said clamping member, a second clamping member, a stop secured to said second clamping member and engaging said follower, and an adjusting screw fitted in said nut and having a head rotatably mounted between the second clamping member and said stop.

3. In a loose leaf binder, a follower having a hole therethrough for receiving a post, a clamping member longitudinally movable with respect to the follower and having a slot adapted to receive said post, a nut carried by said clamping member, a second clamping member, an adjusting screw fitted in said nut and adapted to bear against said second clamping member, and a stop engaging one of said clamping members and said follower for limiting the movement of the clamping member which is engaged by 60 the stop.

4. In a loose leaf binder, a follower having a hole therethrough for receiving a post, a longitudinally movable clamping member carried by the follower and having a slot for receiving therethrough said post, a nut car-

ried by said clamping member, an adjusting screw fitted in said nut, a second clamping member rotatably engaging said adjusting screw, and a stop engaging said second clamping member and said follower for 70 limiting the movement of said second clamping member.

5. In a loose leaf binder, a tubular follower having a hole therethrough for receiving a post and provided with an opening, a clamping member in said follower and provided with a slot for receiving therethrough said post, a nut carried by said clamping member, a second clamping member, an adjusting screw fitted in said nut and rotatably 80 engaging said second clamping member, and a stop mounted in said opening in the follower and engaging one of said clamping members for limiting the movement thereof.

6. In a loose leaf binder, a follower having a hole therethrough for receiving a post, a clamping member having a slot for receiving said post, a nut carried by said clamping member, a second clamping member, a stop carried by said second clamping member and adapted to engage the follower, and an adjusting screw fitted in said nut and having a head rotatably mounted between said stop and said second clamping member and engaging at opposite ends said stop and said 95 second clamping member.

7. In a loose leaf binder, a follower having a hole therethrough for receiving a post, a clamping member having a slot for receiving said post, a nut carried by said clamping member, a second clamping member having coöperating arms inwardly turned, a stop embraced by said arms and adapted to engage the follower, and an adjusting screw fitted in said nut and having a head embraced by and rotatably mounted between the stop and second clamping member.

8. In a loose leaf binder, a tubular follower having a hole therethrough for receiving a post, a clamping member longitudinally movable in said follower and having a slot for receiving said post, a nut carried by said clamping member, a second clamping member, a stop adapted to engage said follower and embraced by said second clamping member, and an adjusting screw fitted in said nut and having a head mounted rotatably between and embraced by said stop and said second clamping member.

9. In a loose leaf binder, a follower having a hole therethrough for receiving a post, a clamping member having a slot for receiving said post, a nut carried by said clamping member, an adjusting screw fitted in said nut and having a head, a second clamping member having inwardly turned coöperating arms, and a stop adapted to engage said follower and disposed between and embraced by said arms, said head being embraced at opposite ends by said stop and 130

- said second clamping member and rotatable therebetween.
10. In a loose leaf binder, a follower having a hole therethrough for receiving a post, 5 a clamping member having at one end a slot for receiving said post, the outer end of said slot being contracted, a nut fitted in the slot and provided at its outer side with a transverse slot having mounted therein inwardly 10 extending portions of the clamping member, an adjusting screw fitted in said nut, and a second clamping member rotatably engaged by said adjusting screw.
11. In a loose leaf binder, a follower having a hole therethrough for receiving a post, 15 a clamping member, a nut carried by the clamping member, an adjusting screw fitted in said nut, a second clamping member rotatably engaged by said adjusting screw, 20 and a stop adapted to engage said follower and carried by one of said clamping members.
12. In a loose leaf binder, a follower having a hole therethrough for receiving a post 25 and provided with an opening, a clamping member, a nut carried by said clamping member, an adjusting screw fitted in said nut and provided with a head, a second clamping member against which one side of 30 said head is rotatable, and a stop extending into said opening and engaging the second
- clamping member at the opposite side of said head.
13. In a loose leaf binder, a follower having a hole therethrough for receiving a post, 35 a clamping member, a nut carried by the clamping member, a non-rotatable clamping member, an adjusting screw fitted in said nut and rotatably engaging the non-rotatable clamping member, and means adapted to 40 engage said follower for limiting the movement lengthwise thereof of one of said clamping members.
14. In a loose leaf binder, a follower having two holes therethrough for receiving respectively two posts, a clamping member adapted to engage one side of one of said posts, a second clamping member adapted to engage the opposite side of the other post, 45 a nut carried by one of said clamping members, a screw fitted in said nut and engaging the other clamping member, and a stop carried by one of said clamping members and adapted to engage said follower.

In testimony whereof I have signed my 55 name to this specification in presence of two subscribing witnesses.

WILLIAM P. PITTS.
